J. L. MOTT.

Cooking Stove.

No. 10,048.

Patented Sept. 27, 1853.

UNITED STATES PATENT OFFICE.

JORDAN L. MOTT, OF NEW YORK, N. Y.

COOKING-STOVE.

Specification of Letters Patent No. 10,048, dated September 27, 1853.

To all whom it may concern:

Be it known that I, JORDAN L. MOTT, of New York city, New York, have invented certain new and useful Improvements in 5 Cooking Stoves and Ranges, and that the following is a full, clear, and exact description thereof, reference being had to the accompanying drawings, making part of this specification, in which—

10 Figure 1, is a longitudinal, and Fig. 2, a cross section of a stove with my improvement applied. Fig. 3, separate views of the flue tubes with the improvement appended; and Fig. 4, is a horizontal section just below the top plate of the bottom flue.

15 In the stove described in Letters Patent granted to me bearing date the 12th of June 1849, the products of combustion pass in a single sheet over the top of the oven 20 and down the back, then pass through a series of flue tubes arranged side by side at the bottom of the oven, and then return in a single sheet through a flue below; there being spaces left between the several flue 25 tubes to permit the heat radiated by the entire surface of the flue tubes and the top plate of the flue below to circulate and pass up into the oven. The mode of construction of this stove heretofore practised, was to 30 cast and connect together the several flue tubes, and to make, and put in the top plate of the bottom flue separately. This mode of construction has given rise to two serious practical difficulties. The plate being cast 35 or made separately and simply laid in its place to give access to the flue below for cleaning it, warps and buckles, and hence is attended with difficulty; but the most serious objection arises from the want of knowl- 40 edge on the part of those using stoves and ranges on this plan. When the series of flue tubes are taken out for cleaning, the top plate of this bottom flue, looks like, and is often taken, by such persons, for the bot- 45 tom plate of the stove and having cleaned the top of it, they replace the series of flue tubes, taking for granted that the whole of the flue space has been cleaned, while, in fact, they have left uncleansed the flue space 50 which is most liable to be choked by soot and ashes. In this way stoves and ranges of this kind have often been rendered inefficient in the baking part.

The object of my invention is to avoid 55 the difficulties heretofore experienced and pointed out above, and to this end the nature

of my invention consists in connecting the top plate of the bottom flue with the series of flue tubes, whether by casting the whole at once, or by attaching them together, so that in taking out the series of flue tubes for cleaning, the said top plate of the flue below shall be removed at the same time, and thereby expose to view the flue space below, while at the same time the said top 60 plate will be prevented from warping and buckling.

Various plans have been tried to facilitate the operation of emptying the grates of stoves, but so far as my knowledge ex- 70 tends they are all attended with trouble, which prevents their successful use.

The object of the second part of my invention, is to produce a mode of liberating the grate, so that it shall clear itself of 75 cinder, &c., and combine therewith a self acting catch to hold the grate in place, but so arranged that its operation shall not be impeded by the deposit of cinder and ashes. To this end the nature of this part of my 80 invention consists in hanging the grate on journals at the sides and at or near the top front edge so that when liberated, the bottom of the grate will swing forward to discharge its contents freely, when this is com- 85 bined with a lever catch, to catch and secure the bottom of the grate when pushed back, the said lever catch or latch working by the weight of its arm, and being fitted between projecting flanges on an in- 90 clined bottom plate which extends from the back of the ash pit, with a considerable slope to the ash receiver in the front apron, so that when the contents of the grate are 95 emptied, they will run down and leave the latch free to act when the grate is pushed back.

In the accompanying drawings *a*, represents the series of bottom flue tubes arranged side by side with spaces *b*, *b*, between them; and *c*, a plate below and at some distance therefrom. All these are connected and held together by end plates *d*, *d*, so that they can be taken out and replaced through the door of the oven *e*, the plate *c*, when in place, constituting the top plate of the bottom flue *f*, below the flue tubes, and the spaces between the several flue tubes, and between them and the plate, *c*, permit the passage into the oven of the heat radiated from all these surfaces. 100

The products of combustion from the fire place *g*, pass in a single sheet over the oven,

then down the back flue *h*, then through the series of flue tubes *a*, to the front, thence into the flue *f* below, around the end of a diagonal partition *i*, to a vertical flue *j*, at 5 the end of the oven, and out to the chimney. The diagonal position of this partition, enables me to discharge the products of combustion through a flue at the ends and at right angles to the plane of the descending 10 flue, and at the same time to spread the heat over the entire surface of the bottom flue, which could not be without this partition, as in that case the products of combustion would take the most direct line to the vertical flue and leave an angle of the oven 15 without efficient heat.

The grate *k*, is formed with journals at the end of the top front bar fitted to turn in the jambs. 20 The bottom plate *l*, below the grate inclines downward from the back plate of the fire place, to the ash pan *m*, in front, so that when the contents of the grate fall into it they will slide down into the ash pan. The 25 plate is also formed with two flanches between which is fitted a lever *n*, the upper end of which forms a latch to hold the grate in place, and the forward end is weighted to make the whole lever act as a self acting 30 latch.

The flanches protect the latch lever, so that ashes and cinder falling down will not clog the latch and prevent it from working.

I do not claim as my invention any particular mode of securing the top plate of the 35 bottom flue, to the series of flue tubes, this may be done in various ways; but

What I do claim as my invention and desire to secure by Letters Patent, is—

1. Connecting the top plate of the bottom 40 flue with the lower part of the series of flue tubes, so that in taking out the series of flue tubes for cleaning, the said top plate of the flue below, shall be removed at the same time, and thereby expose to view the lower 45 flue space greatly facilitating the operation of cleaning.

2. I do not claim hanging the grate irrespective of the combination as my invention; what I do claim as my invention is the combination of a swinging grate as described 50 with the self-acting weighted latch connected with the plate below the grate as specified, whereby the contents of the grate can be readily discharged, and the grate readjusted by a slight use of a poker.

JORDAN L. MOTT.
